No. 760,954.

PATENTED MAY 24, 1904.

R. CALLAGHAN.

RAIL JOINT.

APPLICATION FILED JAN. 16, 1904.

NO MODEL.

UNITED STATES PATENT OFFICE.

ROBERT CALLAGHAN, OF PHILADELPHIA, PENNSYLVANIA.

RAIL-JOINT.

SPECIFICATION forming part of Letters Patent No. 760,954, dated May 24, 1904.

Application filed January 16, 1904. Serial No. 189,303. (No model.)

To all whom it may concern:

Be it known that I, ROBERT CALLAGHAN, a citizen of the United States, residing in Philadelphia, Pennsylvania, have invented certain 5 Improvements in Rail-Joints, of which the following is a specification.

The main object of my invention is to so form the abutting ends of railway-rails that the fish-plates can be dispensed with and that 10 the rails at the joint will be held both laterally and longitudinally, allowing only for the usual longitudinal expansion and contraction.

In the accompanying drawings, Figure 1 is a perspective view showing my improved rail- 15 joint. Fig. 2 is a side view. Fig. 3 is a transverse section on the line 3 3, Fig. 2; and Fig. 4 is a perspective view showing two rails detached.

A and A' are ordinary T-rails, each rail 20 having a portion of the end cut away at a, the cut extending through the head and web of the rail, so that when the two rails are placed together the portion a of one rail fits against the portion a of the other, making a continuous 25 tread for the wheels. The entire base-flange of each rail is cut away at b, leaving a portion a'. When the two rails are coupled, as in Figs. 1 and 2, the portion a' of one rail will rest in the space b of the adjoining rail. It 30 will be noticed that the portion a' of the base-flange has a bearing-surface a'', upon which rests the bridge-section c of the adjoining rail, so that while an interlock is formed the rail is supported throughout by a base-flange. 35 The webs are perforated at z, as shown, and ordinary bolts and nuts I are used to fasten the rails together without the use of fish-plates, although in some instances fish-plates or washers may be used, if desired.

40 It will be seen that I am enabled to make a satisfactory rail-joint without the use of fish-plates, and the joint may be so made that the end of one rail will snugly fit the end of another, and the ends of the rails will be held 45 against both longitudinal and lateral displacement.

The base-flange at the portion a' of the rail extending the full width of the flange enables me to give the rail the full bearing at its extreme end, and the base-flange can be fastened 50 to the ties, making a very secure and substantial joint.

I claim as my invention—

1. The combination of two rails, each having a portion of the head and web cut away 55 so that one will fit against the other and having the base-flange some distance from the end recessed, so that the full portion of the base-flange at the end of one rail will fit into the recessed portion of the base-flange of the other 60 rail, substantially as described.

2. The combination of two abutting rails, each rail having part of the web and head cut away and having the base-flange some distance from the end entirely cut away to form a re- 65 cess, so that the full portion of the base-flange at the end of one rail will fit into the recessed portion of the adjoining rail, holes in the overlapping portions of the rails, and bolts for securing the two rails together, substantially 70 as described.

3. The combination of two rails, each rail having a part of the head and web cut away at one end so that the cut-away portion of one rail will fit against the cut-away portion of the other, 75 each rail having part of its base-flange some distance from the end recessed, forming an interlocking section at the end of the rail, said section fitting into the recess in the adjoining rail and having a bearing-surface on 80 which rests the web of the adjoining rail, and bolts for securing the said sections together, substantially as described.

In testimony whereof I have signed my name to this specification in the presence of two sub- 85 scribing witnesses.

ROBERT CALLAGHAN.
